DESIGN FOR A PORTABLE REFRIGERATOR

Jacob Zitzerman, Brooklyn, N. Y.

Application November 10, 1938, Serial No. 80,999

Term of patent 14 years

To all whom it may concern:

Be it known that I, Jacob Zitzerman, a citizen of the United States and resident of Brooklyn, in the county of Kings and State of New York, have invented a new, original, and ornamental Design for a Portable Refrigerator, of which the following is a specification, reference being had to the accompanying drawing, forming part thereof.

In the drawing:

Fig. 1 is a perspective view of a portable refrigerator showing my new design.

Fig. 2 is a similar view with the doors in opened position.

I claim:

The ornamental design for a portable refrigerator, substantially as shown.

JACOB ZITZERMAN.
